WRIST SUPPORT FOR USE IN BOWLING

Norman S. Borenstein, 14431 Galy,
Tustin, Calif. 92680

Filed Aug. 10, 1973, Ser. No. 387,338

Term of patent 14 years

Int. Cl. D2—02

U.S. Cl. D2—27

FIG. 1.

FIG. 3.

FIG. 2.

FIG. 4.

FIG. 1 is a side perspective view of a wrist support showing my new design;

FIG. 2 is a perspective view of the other side;

FIG. 3 is an outside plan view thereof; and

FIG. 4 is an inside plan view.

I claim:

The ornamental design for a wrist support for use in bowling, as shown.
